UNITED STATES PATENT OFFICE.

LONNIE M. MOORE, OF HOPKINSVILLE, KENTUCKY.

SHADE-BRACKET ROD.

Application filed September 23, 1922. Serial No. 590,157.

To all whom it may concern:

Be it known that I, LONNIE M. MOORE, a citizen of the United States, residing at Hopkinsville, in the county of Christian and State of Kentucky, have invented certain new and useful Improvements in Shade-Bracket Rods, of which the following is a specification.

This invention relates to curtain rods and 10 more particularly to such rods as are employed in connection with double windows.

The object of the invention is to provide a simple, convenient and effective curtain rod which may be easily adjusted to fit a double 15 window of any width, within the limits of the device, and which may be easily attached to and detached from the window casing.

The invention also contemplates the provision of a curtain rod of the character described, on which shade brackets may be adjustably mounted. In order that the invention may be readily understood, reference is had to the accompanying drawing, in which:

Fig. 1 is a front elevation of the upper 25 part of a double window, showing my improved rod applied thereto;

Fig. 2 is a plan view thereof, the window frame or casing being shown in section;

Fig. 3 is a section on an enlarged scale, 30 substantially on the line 3—3 of Fig. 2, looking in the direction of the arrows;

Fig. 4 is a fragmentary longitudinal section on an enlarged scale, through one of the supporting arms hereinafter described; 35 and

Fig. 5 is a face view of the supporting arm illustrated in Fig. 4, the rod being shown in section.

Referring to the drawings in detail, the 40 double window is illustrated as comprising the usual side members 1 and middle frame member 2.

My improved rod comprises a central section 3 and two end sections 4, the sections 45 telescoping into the ends of the central section 3 and rigidly held therein by means of tension springs 5 having their ends engaged over hooks formed by tongues 6 struck out from the body of the sections 3 and 4.

The shape of these sections and the manner 50 in which the springs 5 and tongues 6 are constructed and assembled is the same as shown in my prior Patent No. 1,470,578, dated Oct. 9, 1923.

In order to attach the central section 3 of my improved curtain rod to the middle

frame member 2 of the double window, so that it may be rigidly supported, I provide a pair of supporting arms 9, each secured to a sleeve 7 slidably mounted on the central 60 section 3 of the rod and adapted to be secured in adjusted position by means of a set screw 8. The arms 9 carry at their ends, prongs or spurs 10, which are adapted to bite into the side faces of the middle frame 65 member 2, as shown in Fig. 2, two of such spurs being employed in connection with each arm 9 so as to rigidly hold the same.

Similar spurs 4^a are carried at the inwardly bent ends of the sections 4 and are 70 adapted to bite into the outer faces of the side frame members 1, under the influence of the springs 5.

In order to support shade rollers on my improved curtain rod, I provide four shade 75 brackets 11, 12, 13 and 14. Two of these brackets, 11 and 12, are secured to the central section 3, at a point intermediate the two supporting arms 9, while the other brackets, 13 and 14, are mounted upon the sections 4, 80 adjacent the side frame members 1.

The manner of attaching these shade brackets to the rod is the same as that described in detail in my above mentioned application. That is to say, each bracket, such as 11, is secured to a base plate 15, which carries at its upper end a resilient clip 16, attached to the plate 15 at one end, as by means of a rivet 17, the plate 15 and clip 16 being arranged to straddle over the rod. 90

The rod sections 3 and 4 each are provided with a series of perforations 19, adjacent the said brackets and each clip 16 carries one or more inwardly projecting studs 18, which are adapted to snap into and engage any desired one of the holes 19. A tongue 20 is preferably struck up from the base plate 15 and is so positioned as to engage under the curtain rod, as clearly shown in Fig. 3. Thus, by disengaging the studs 18 from the holes 19, the said brackets may be adjusted longitudinally of the rod sections and secured thereto at any desired point. It will be understood that all of the said brackets 11, 12, 13 and 14 are mounted on the rod sections by this same means, as shown in Fig. 100 105 110

3. It will be noted that the sleeves 7 and supporting arms 9 may be adjusted longitudinally of the central section 3, so as to accommodate middle frame members of different widths, the arms being simply pushed into engagement with the opposite sides of

by means of the set screws 8. Thus, the frame member and secured in position middle section 3 of the rod is rigidly supported and the spurs 4^a carried by the end sections 4 are pressed into the side edges of the frame members 1, by reason of the tension of the springs 5, which are secured at one end to the members 4 and at the other end to the fixed central member 3.

10 What I claim is:

1. A self alining rod for double windows comprising a straight, substantially rigid central section, means for securing said section to the middle frame member of the window so that it is rigidly supported thereby, said section extending horizontally across such middle frame member and having its ends projecting partially over each window opening, a pair of substantially rigid end sections adjustably connected to and in alignment with the projecting ends of said central section to form therewith a continuous rod, lying in a single plane, means for securing the outer ends of the said end sections to the side edges of the side frame members of the window, the inner ends of said end sections being supported by said central section, a pair of shade brackets mounted on said central section adjacent the securing means,

and an additional shade bracket carried by each of said end sections.

2. A shade bracket rod for double windows comprising a straight central and two end sections, adjustably connected, and a pair of arms, slidably mounted on said central section, and adapted to engage opposite side faces of the vertical middle frame member of the window.

3. A shade bracket rod for double windows, said rod being provided with a pair of arms adjustable toward and from each other, longitudinally of said rod and having at their ends spurs adapted to bite into the opposite side faces of the vertical middle frame member of the window, so as to support said rod.

4. A shade bracket rod for double windows, said rod being provided with a pair of arms adjustable toward and from each other, longitudinally of said rod and having at their ends spurs adapted to bite into the opposite side faces of the middle frame member of the window, and a pair of shade brackets secured to said rod at a point between said arms.

In testimony whereof I affix my signature.

LONNIE M. MOORE.

Certificate of Correction.

It is hereby certified that in Letters Patent No. 1,519,548, granted December 16, 1924, upon the application of Lonnie M. Moore, of Hopkinsville, Kentucky, for an improvement in "Shade-Bracket Rods," an error appears in the printed specification requiring correction as follows: Page 1, after line 112 insert the words *the frame member and secured in position*, and page 2, line 2, strike out the words "the frame member and secured in position"; and that the said Letters Patent should be read with this correction therein that the same may conform to the record of the case in the Patent Office.

Signed and sealed this 10th day of March, A. D. 1925.

[SEAL.]

KARL FENNING,
Acting Commissioner of Patents.
